HEAT ACTUATED SAFETY SHUTOFF VALVE

Charles M. Bailey, San Francisco, Calif., assignor
to Charles M. Bailey Co., Inc., a corporation

Application September 11, 1940, Serial No. 356,263

3 Claims. (Cl. 137—139)

This invention relates to high-pressure gas valves such as are used in power plants, and particularly represents modifications of and additions to the valve structure shown in U. S. Patent No. 2,229,543, dated January 21, 1941.

My principal object now is to provide a control means for the valve so arranged that while the valve will normally remain open, it will be closed by reason of excessive heat caused by a fire immediately adjacent the valve, or independently by a fire at any point in the plant relatively remote from the valve.

The figure on the drawing is an elevation, partly in section, of my improved valve control means.

Referring now more particularly to the characters of reference on the drawing, the valve itself is of the globe type, and includes a body 1 having a vertically movable valve disc 2 adapted to cooperate with a seat 3 and raised from said seat when open.

A stem 4 projects upwardly from the disc, and passes through a packing gland 5 on top of the body. At its upper end the stem is connected to a substantially horizontal lever 6 which intermediate its ends but close to the stem, is pivoted as at 7 on a cage 8 upstanding from the valve body. A substantially vertical trigger 9 is pivoted on the cage in line with and beyond the adjacent end of the lever, the trigger having a lip 9a on its lower end underhanging the lever when the latter is moved down at its opposite end to open the valve as shown in the drawing. A tension spring 10 is connected to the lever beyond the stem 4 and to the cage above said lever to exert an upward pull on the adjacent portion of the lever, which tends to close the valve.

A substantially horizontal holding arm 11 is pivoted intermediate its ends as at P on the cage above the lever pivot 7 and extends lengthwise of the lever toward the trigger. At its trigger end, said arm normally engages a seating notch 12 cut in the edge of the trigger above its pivot and on the same side as lip 9a; such engagement preventing the trigger swinging in a direction to move the lip clear of the lever, as will be evident. As soon as the trigger end of the arm is raised clear of the seating notch, however, the lever will be released and the valve will be closed by the action of spring 10 on said lever.

In order to thus release the arm and cause the trigger to trip by reason of fire in the immediate vicinity of the valve, I provide the following arrangement: Secured at one end to the end of the arm 11 furthest from the trigger is a chain

13 or other flexible element, which at its other end is connected to a weight 14. This weight is normally supported above the arm so that the chain is somewhat slack by means of a readily fusible link 15 projecting from the ball and which is hung from a hook 16 supported from the cage above the weight and trigger.

It will therefore be seen that fire heat adjacent the valve will cause the link to melt. The ball will then drop below the arm as far as the chain will permit, causing a sudden downward pull to be exerted on the adjacent end of the arm. This will of course raise the other end of said arm clear of the trigger, releasing the latter and allowing the valve to close.

In order to also cause the valve to close by fire heat at points other than immediately adjacent the valve, I provide the following structure: The arm 11, between its pivot P and the trigger, is provided with a cross pin 17, which slides in a vertical slot 18 in a yoke 19. This yoke depends from a stem 20 which at its upper end is connected to the underside of a disc 21. This disc is yieldably pressed upward by a spring 22 of adjustable pressure. Directly above and engaging the disc is a diaphragm 23 mounted in a housing 24 supported from the cage 8.

A water pressure pipe 25 is connected intermediate its ends to the housing 24 above the diaphragm by a lateral 26. The pipe has a pressure reducing valve 27 therein ahead of the lateral, and a restriction 28 between the reducing valve and said lateral. The pipe extends any desired distance beyond the lateral and at convenient points, such as in different rooms separated by a wall 29, is provided with overhead sprinkler heads indicated diagrammatically at 30 and which are of that conventional type which open only when affected by fire heat in the vicinity.

The spring 22 is set to counteract the normal water pressure in the diaphragm housing, and it will be seen that as soon as such pressure is relieved by the opening of any sprinkler, the spring 22 will act to lift disc 21 and stem 20 attached thereto, and will raise the adjacent portion of the holding arm 11. This will release the trigger and allow the valve to close in the same manner as by the action of the weight 14 previously described.

From the foregoing description it will be readily seen that I have produced such a device as substantially fulfills the objects of the invention as set forth herein.

While this specification sets forth in detail the present and preferred construction of the de-

vice, still in practice such deviations from such detail may be resorted to as do not form a departure from the spirit of the invention, as defined by the appended claims.

Having thus described my invention, what I claim as new and useful and desire to secure by Letters Patent is:

1. A safety control mechanism for a self-closing valve having releasable means associated therewith to normally hold the valve open, said means including a member movable to release the same, said control mechanism comprising a pressure responsive unit adapted to be arranged in communication with a fluid pressure conduit, means connecting said pressure responsive unit with said holding means whereby the unit is operative to release said holding means upon predetermined variation in the fluid pressure in said conduit, a separate unit responsive to fire heat adjacent the valve, and separate means connecting said separate unit and the common holding means whereby said separate unit is operative to release said holding means; the connecting means for the pressure responsive unit having limited loose-play connection with said member, and the separate connecting means for said fire-heat responsive unit comprising a normally slack flexible element of non-combustible material connected to said member whereby either unit may separately and independently move said member and release said holding means.

2. A safety control mechanism for a self-closing valve having releasable means associated therewith to normally hold the valve open, said means including a vertically movable member; said control mechanism comprising a pressure responsive unit adapted to be arranged in communication with a fluid pressure conduit, means connecting said pressure responsive unit with said holding means whereby the unit is operative to release said holding means upon predetermined variation in the fluid pressure in said conduit, a separate unit responsive to fire heat adjacent the valve, and separate means connecting said separate unit and the common holding means

- valve, and separate means connecting said separate unit and the common holding means whereby said separate unit is operative to release said holding means upon predetermined fire heat adjacent the valve; the connecting means for the pressure responsive unit having loose play connection with said member, the fire heat responsive unit including an elevated weight suspended from a fusible element, and the connecting means for said fire heat responsive unit comprising a normally slack flexible element of non-combustible material connected between the weight and said member, whereby either unit may separately and independently move said member and release said holding means.
3. A safety control mechanism for a self-closing valve having releasable means associated therewith to normally hold the valve open, said means including a vertically movable member; 20 said control mechanism comprising a pressure responsive unit adapted to be arranged in communication with a fluid pressure conduit, means connecting said pressure responsive unit with said holding means whereby the unit is operative to release said holding means upon predetermined variation in the fluid pressure in said conduit, a separate unit responsive to fire heat adjacent the valve, and separate means connecting said separate unit and the common holding means 25 whereby said separate unit is operative to release said holding means upon predetermined fire heat adjacent the valve; the connecting means for the pressure responsive unit having loose play connection with said member, the fire heat responsive unit including an elevated weight suspended from a fusible element, and the connecting means for said fire heat responsive unit comprising a metal chain fixed on and depending from the weight to a point below said member and thence looping 30 upward and connected thereto, whereby either unit may separately and independently move said member and release said holding means.
- CHARLES M. BAILEY.
